UNITED STATES PATENT OFFICE.

JOHN W. ECKMAN, OF DECATUR, ILLINOIS

SWIMMING-GLOVE.

1,275,005.

Specification of Letters Patent.

Patented Aug. 6, 1918.

Application filed February 1, 1918. Serial No. 214,950.

To all whom it may concern:

Be it known that I, JOHN W. ECKMAN, a citizen of the United States, residing at Decatur, in the county of Macon and State of Illinois, have invented new and useful Improvements in Swimming-Gloves, of which the following is a specification.

This invention relates to devices for assisting swimmers in forcing their way 10 through the water and particularly to devices of this class which are adapted to be fitted upon the hands of the swimmer.

The primary object of the invention is to produce a glove which may be readily 15 arranged on the hands of the swimmer in a manner to prevent the entrance of water between the glove and the swimmer's hands, the glove having its outer edge provided with a continuous web, and the edge of the 20 web being formed with a flange, while connecting the said flange with the fingers of the glove are ribs, the spaces between the ribs and flange comprising what may be termed separate compartments each de- 25 signed to offer a resistance to the water as the glove is propelled through the water, assisting in sustaining the swimmer on the surface of the water.

It is a further object of the invention to 30 produce a device of this character in the nature of a flexible glove which, when straight, as when the fingers of the hand of the swimmer are open provides a plurality of pockets or compartments, which when 35 filled with water, on the stroke of the swimmer increases the buoyancy of the swimmer's body, the elements comprising the pockets or compartments being of a flexible nature so that the side movement 40 of the hand will result in the collapsing of the said pockets permitting the swimmer, after making a stroke to thus return his hand after encountering undue resistance from the water, the said glove, also when the 45 fingers of the swimmer are brought together likewise offering little resistance to the water should the swimmer find it convenient to close his fingers upon the return stroke in swimming.

It is a still further object of the invention 50 to produce a swimming glove which shall be of a comparatively simple construction, cheap to manufacture, easily applied to or taken from the hand of the user, and 55 thoroughly efficient for the purpose intended.

Other objects and advantages will appear as the nature of the invention is better understood, reference being had to the accompanying drawings, in which,

Fig. 1 is a top plan view of a swimmer's glove with the fingers straightened out but in close parallel and unspread position.

Fig. 2 is a bottom plan view with the 65 fingers outstretched and also spread widely from each other.

Fig. 3 is a sectional view approximately on the line 3—3 of Fig. 2.

Fig. 4 is a sectional view approximately 70 on the line 4—4 of Fig. 2.

My improved glove is preferably formed, molded or otherwise constructed, of a single piece of suitable elastic material, such as rubber, and comprising a wrist portion 1, back and palm portions 2 and 3, a tubular thumb portion 4, and finger portions 5.

Between the wrist portion 1, the thumb and finger portions 4 and 5 respectively is 80 arranged a web 6 which extends a suitable distance outward from the ends of the thumb and finger portions. The web 6 is provided, upon its outer edge with a continuous right angular flange 7, said flange 85 having its ends connected with the opposite sides of the wrist portion 1 of the glove. The flange 7 is designed to be retained at a right angle with respect to the web 6 through the medium of integrally formed 90 ribs 8 provided centrally on the thumb piece 4 and finger pieces 5, of the palm side of the glove.

The ribs and flange divide the palm side of the glove into a plurality of compartments or pockets designed to offer a great resistance to the water when the swimmer's hand is propelled therethrough. The ribs 8 gradually decrease in width from their connection with the flange 7 to the terminals of the finger and thumb portions of the glove. The wrist portion of the glove has its outer end preferably provided with an elastic band 9 that prevents the entrance of water between the glove and the hand of 105 the user. When the fingers are brought together, as illustrated in Fig. 1, the collapsing of the web 6 and the folding of the flange 7 collapses the pocket 9 so that slight resistance will be offered by the 110 water on the return stroke of the swimmer. The flange 7 and the ribs 8 being formed of

some suitable elastic material will yield when the swimmer passes his hand sidewise through the water, so that the return stroke may be made in this manner instead of bringing his fingers together.

From the foregoing description, when taken in connection with the drawing, the simplicity and advantages of the construction, will, it is thought, be apparent without further detailed description.

What I claim is:

1. A glove of the class described comprising a hollow body portion, a series of finger portions extending from the body portion, a flexible web between the fingers and the sides of the body portion, a continuous angular flange on the outer edge of the web, and angular rib members between

the flange and the finger portions of the glove.

2. A swimmer's glove including a body and a finger portion, a web arranged between the body and the finger portions at the back of the glove, said web being extended outward from the tips of the fingers and being provided with a continuous angular flange, rib members connected with the flange and arranged centrally of the finger portions of the glove and said ribs gradually decreasing in width from their connection with the flanges to their opposite terminals.

In testimony whereof I affix my signature.

JOHN W. ECKMAN.
